FILLING STOP MOTION

Edward C. Nichols, Upton, Mass., assignor to
Draper Corporation, Hopedale, Mass., a corpora-
tion of Maine

Application January 8, 1935, Serial No. 875

5 Claims. (Cl. 139—370)

The present invention pertains to loom stop motions and has more particular reference to filling stop motions of the type having a knock-off lever.

5 In looms of the type mentioned, a filling fork slide is connected to positively move the knock-off lever upon filling failure, thereby moving a shipper and effecting loom stoppage. The filling fork slide of such stop motions does not return 10 to its normal running position until after the loom has been restarted, thus necessitating some means for releasing the connections to the shipper in order to prevent interference with the operation of the latter.

15 The present invention has for its principal object the provision of a filling stop motion of the type mentioned, wherein the shipper knock-off lever is comprised of separate sections which are normally rigidly connected together but which 20 are automatically released, to thereby free the shipper-actuating section, at the end of each knock-off movement.

The preferred embodiment of the invention is illustrated on the accompanying drawings, of 25 which:

Fig. 1 is a plan view of the stop motion comprising said preferred embodiment;

Fig. 2 is a front elevational view of part of the mechanism of Fig. 1;

30 Fig. 3 is fragmentary plan view of the knock-off parts, the knock-off lever thereof being partially broken away;

Fig. 4 is a view similar to Fig. 3 but showing the parts in loom stopping position; and

35 Fig. 5 is a vertical section view taken approximately on line 5—5 Fig. 1.

The loom shown on the drawings is of conventional design except as hereinafter described and such loom is accordingly but fragmentarily illustrated. Of the conventional construction there is shown a part of the frame including left hand loom side 1 and breast beam 2, a part of the reciprocating lay 3 which carries a shuttle box 4 and along which the shuttle 5 is picked, and the 40 loom controls represented by shipper 6. The shipper is moved forwardly to the full line position of Fig. 1 to cause the loom to run, and is moved rearwardly to the dotted line position to effect loom stoppage.

50 The filling stop motion shown includes a fork grate 7 mounted on the lay adjacent the mouth of the shuttle box, and a side filling fork 8. The fork is pivotally mounted on a slide 9 which is adapted to slide forwardly and rearwardly in a 55 guideway 10. When the fork detects absence of

filling it catches onto a hook 11 carried by the forwardly and rearwardly reciprocating weft hammer 12. The weft hammer thus positively moves the filling fork slide forwardly upon occurrence of filling failure.

5 The stop motion as thus far described is of usual construction now well known in the art. The connections between the filling fork slide and the shipper for operating the latter from the former are, however, of the present invention. 10 The preferred forms of such connections will now be described.

A lug 13 projects from one side of the filling fork slide in position to engage a nose 14 on an arm 15 which may be pivoted to the breast beam 15 at 16. A spring 17 has one end connected to the arm and the other end connected to the shipper knock-off lever to be described, the spring serving to hold both the arm and the lever rearwardly. The lug and arm are merely a convenient means 20 of transmitting forward movement of the slide to the knock-off lever.

25 The shipper knock-off lever of the present invention is made sectional. That is, it is made up of separate sections. In the preferred embodiment one section has an arm 18 which is engaged by a depending lug 19 on the arm 15, and an arm 20 which projects toward the shipper. This section is pivoted intermediate its ends on a pin 21 in bracket 22 which bracket is fixed to 30 the loom frame. The other section 23 is the shipper engaging section and it preferably overlaps the arm 20 of the first section and is pivoted on the same axis.

35 The sections of the knock-off lever are normally rigidly connected together as by means of a plunger slidably mounted on one section and engaging the other section. As shown, a lug 24 projects downwardly from the section 23 to engage the front side of the arm 20 and the plunger 25 is slidably mounted in a guideway in the arm 20, the plunger being urged along the arm by a spring 26 so as to normally engage a shoulder 27 on the section 23. When the plunger is projected into engagement with the shoulder the 40 two sections of the lever are rigidly connected together so that the knock-off lever serves to move the shipper handle in the same manner as the one piece knock-off lever of prior constructions. The connecting plunger is housed 45 between the overlapping parts of the lever sections so as to be unaffected by accumulations of lint on the loom.

50 Fig. 4 of the drawings shows the stop motion parts in the position which they assume im- 55

mediately upon actuation of the shipper from the filling fork slide.

The slide does not return rearwardly when the loom stops, but remains in its forward position until the loom has been turned over at least one pick. Accordingly, if the sections of the knock-off lever were to remain connected together after the knock-off movement, the lever would project into the path of the shipper and prevent the shipper from being moved to its full on position.

The present invention provides means for disconnecting the sections of the knock-off lever, to thereby free the shipper engaging section thereof, upon and at the end of each knock-off movement of the lever and slide. To this end, the plunger 25 has a projection 28 on the under side thereof in position to be engaged by the fixed cam 29 during the course of the knock-off movement of the lever. The cam may be formed as an unstanding flange on the bracket 22 and it is so shaped and positioned that it withdraws the plunger 25 from engagement with the shoulder 27 approximately at the end of the knock-off movement.

When the sections of the lever are disconnected as above described, the shipper engaging section 23 is freed from control of the slide so that it cannot interfere with the movement of the shipper handle to on position. Such movement will swing the section 23 forwardly to the loom-running position of Figs. 1-3, but will leave the other parts in the loom-stopping position of Fig. 4. Subsequent to the restarting of the loom, the slide 9 will return rearwardly as usual, the spring 17 will move the arm 15 and the lever section 18, 20 to loom-running position, and the spring 26 will move the plunger into engagement with the shoulder 27 thus restoring the connections between the lever sections.

The present invention is in the nature of an improvement over the construction disclosed in patent application of Verner Lindsjo, Serial No. 881, filed of even date herewith.

Having fully disclosed the preferred embodiment of my invention, I claim:

1. In a loom stop motion, loom controls including a shipper, a side filling fork slide, a shipper knock-off lever comprised of separate sections one of which engages said shipper, means engaging the other of said sections for positively imparting knock-off movement to said lever upon movement of said slide, means normally rigidly

connecting said sections together, and means operative by virtue of knock-off movement of said lever for disconnecting the sections thereof and thereby freeing said shipper-engaging section from control of said slide.

2. In a loom stop motion, loom controls including a shipper, a side filling fork slide, a shipper knock-off lever comprised of separate sections one of which engages said shipper, means engaging the other of said sections for positively 10 imparting knock-off movement to said lever upon movement of said slide, a plunger mounted on one of said sections and movable thereon to and from a position wherein it rigidly connects said sections together, and means for moving said 15 plunger from said connecting position to thereby free said shipper engaging section at the end of each knock-off movement of said lever.

3. In a filling stop motion for looms, a shipper knock-off lever comprised of two separate sections pivoted to move together in effecting loom stoppage, a plunger mounted on one of said sections for sliding movement to and from a position wherein it engages the other of said sections and rigidly connects the sections together, and a fixed cam engaging said plunger and sliding the same in a direction to disconnect said sections at the end of each knock-off movement of said lever.

4. In a filling stop motion for looms, a shipper 30 knock-off lever comprised of two separate sections pivoted on a common axis to move together in effecting loom stoppage, one of said sections overlapping the other section, means housed between the overlapping portions of said sections 35 for releasably connecting the same together, and a fixed cam operable by virtue of knock-off movement of said lever to disconnect said sections at the end of each said knock-off movement.

5. In a loom stop motion, loom controls including a shipper, a side filling fork slide, a shipper knock-off lever comprised of separate overlapping sections pivoted on a common axis, one of said sections engaging said shipper, a plunger housed between the overlapping portions of said sections 45 and normally rigidly connecting the same together, means engaging the second of said sections for positively imparting knock-off movement to said lever, and a fixed cam engageable with said plunger for disconnecting said sections 50 at the end of each said knock-off movement.

EDWARD C. NICHOLS.
